UNITED STATES PATENT OFFICE.

JAY H. HALL, OF CLEVELAND HEIGHTS, OHIO, ASSIGNOR TO THE ELECTRIC COTROLLER & MANUFACTURING COMPANY, OF CLEVELAND, OHIO, A CORPORATION OF OHIO.

FRICITION BRAKE.

Application filed October 5, 1925, Serial No. 60,417. Renewed October 18, 1927.

My invention relates to friction brakes, and more particularly to brakes of the spring-applied and electromagnetically-released type. However, certain features are 5 applicable to friction brakes of other types.

It is one of the objects of this invention to construct and arrange the parts so that the brake-drum or wheel can be removed without removing any other part of the brake 10 mechanism or disturbing any of the adjustments. Another object of the invention is to arrange the operating levers and brakeshoe supports so that the bearings are contained in the frame or supporting casting below 15 the center of the brake-wheel, whereby the said frame may be of simple design and may be made sufficiently strong without using an excessive amount of material therein. My invention further relates to combinations of 20 various levers, and their relations to the brake-shoes, and to their lever-actuating means, as hereinafter pointed out in more detail. Other objects appear hereinafter.

Referring to the accompanying drawings, 25 Fig. 1 is a side view with the bearings for the brake-wheel shaft omitted; Fig. 2, a section on the line II-II on Fig. 1; and Fig. 3, an elevation of Fig. 1, looking to the left, the right end of the frame being left off and parts being in section.

Referring to the drawings, 1 designates a 30 metal frame or casting having the spaced-apart sides 2, preferably tied together centrally by the web 3.

4 designates the brake-wheel or drum 35 keyed to the shaft 5, the bearings for the latter being omitted. The brake-wheel turns between the two brake-shoes 6 and 7, the former being supported by the pivot pin 8 in the upper end of the lever 9 pivoted between its ends on the pivot pin 10 supported in the upstanding ears 11 on the right hand end of the frame 1 and on the rear portions of the right hand ends of the sides 2.

The left shoe 7 is pivotally supported by 45 the pin or pivot 13 extending through the shoe and the upper ends of the two oscillatable supports or bars 14 joined by a web 14^a between which bars the shoe is situated. The lower ends of the supports 14 are piv- 50 oted on the pin 15 in the sides 2.

16 is an electromagnet standing at the left of the shoe 7 and having its right hand portion supported by the pin 15 and its left hand portion by the set-screw 17 working in 55 the lug 18 on the back face of the electromagnet and engaging the lug 19 on the end 20 of the frame 1. The electromagnet is so tilted that its active or armature-attracting face 21 is inclined downwardly and towards 60 the right.

The armature 22 of the magnet is pivoted on the pin 15 and is pivotally connected by the pin or pivot 23 to an intermediate portion of the lever 24 whose upper end is pivoted on the pin 13 and whose lower end carries the pin or pivot 25. The link 26 has one end pivoted on the pin 25 and the other on the pin or pivot 27 in the lower end of the lever 9. One side of the frame 1 has the 70 notch 28 through which the pin 27 projects. The frame 1 has at the left side of the notch the lug 29 in which the set-screw 30 works, its right hand end being engageable by the pin 27 upon completion of the opening movement of the shoes to limit such movement. The degree of this movement can be regulated by the set-screw 30. 75

The levers 9 and 24 carry the usual adjusting set-screws 31 and 32 engageable with the outer faces of the lower ends of the brake-shoes 6 and 7 to prevent the upper ends of the shoes from tipping forward when the shoes are released.

The upper end of the armature 22 is provided with the pin 33 carrying the screw-threaded rod 35 through the intermediate block 34 pivoted on the pin 33. The outer end of the rod passes through the lug 36 on the back upper portion of the electromagnet 90 16. A nut 37 having the handle 38 works on the outer end of the rod 35 and is engageable with the outer face of the lug 36. A helical spring 39 surrounds the rod 35 and has one end engaging the inner or right face of the lug 36 and the other end engaging the washer 40 held on the rod in any desired adjustment by the nut 41 so as to give the spring 39 the required expansive force for properly setting or applying the brake-shoes. 95

42 is a coiled spring having one end attached to the web 3 and the other end to the 100

lever 9 for causing the pin 27 to engage the set-screw 30 and for ensuring that both brake-shoes will be opened fully and equally.

The drawings show the armature 22 open 5 and the spring 39 causing the brake to be set. The spring forces the armature to the right. The swinging of the armature to the right causes the pin 23 to move to the right, the lever 24 and the link 26 being 10 moved to the right at the same time. These movements cause the levers 9 and 24 to apply both brake-shoes to the brake-wheel with equal pressure. At the same time the spring 42 is stretched and the pin 27 is 15 moved away from the set-screw 30.

Upon the energization of the electromagnet the armature is swung to the left on Fig. 1, causing the lever 24 and the link 26 to move in the same direction. When the 20 pin 27 engages the set-screw 30, as before described, both brake-shoes are released.

When it is desired to remove the brake-wheel, it is necessary to release the shaft 5 from its bearings, not shown, and to lift 25 the brake-wheel directly upwards. The brake-shoes will turn freely outward so as to allow the brake-wheel to pass easily upwardly between them. The process of removing the brake-wheel is facilitated by 30 causing the armature to move toward the magnet either by the energization of the magnet or by turning the nut 37 against the lug. This movement of the armature to closing position causes the brake-shoes to 35 move farther apart so as to allow the brake-wheel to move upwardly without substantial resistance from the rest of the brake mechanism. It is further seen that the brake-wheel is removable without removing 40 any part of the brake mechanism or disturbing any of the adjustments. It can be as easily replaced by proceeding in the reverse order.

As the brake-shoes wear, the air gap between the magnet and armature increases. The set-screw 17 allows the inclination of the magnet to be adjusted to change the air gap between the magnet and armature. The mounting of the magnet on the pin 15 at 45 some distance forwardly of the center of gravity of the magnet tends to hold the magnet from moving, it being intended that it shall remain stationary when the armature moves.

55 I claim:—

1. In a friction brake, two brake-shoes arranged to engage the periphery of the brake-drum at opposite sides of the shaft, a frame, and means supported by the frame 59 for supporting and operating the brake-shoes, the frame and the said means permitting at all times the free movement of the brake-drum laterally entirely from between the brake-shoes.

65 2. In a friction brake, a shaft, a brake-

drum thereon, two brake-shoes arranged at opposite sides of the shaft and adapted to frictionally engage the periphery of the drum, and means for supporting and operating the brake-shoes, the said means being arranged so that the brake-drum may be removed transversely from between the brake-shoes without removing any element or changing any adjustment.

3. In a friction brake, a shaft, a brake- 75 drum thereon, two brake-shoes arranged at opposite sides of the shaft and adapted to frictionally engage the periphery of the drum, and means for supporting and operating the brake-shoes, the said means being arranged at only three sides of the brake-drum, leaving the remaining side free for the passage of the brake-drum laterally from between the brake-shoes.

4. In a friction brake, a brake-drum, two 85 brake-shoes arranged at opposite sides of the drum and adapted to frictionally engage the same, a frame beneath the brake-drum, a lever supported between its ends by the frame and supporting at one end one of the 90 brake-shoes, a second lever connected at one end to the remaining brake-shoe, means operatively connecting together the remaining ends of the levers, means supported by the frame and supporting the second brake-shoe, and means for applying force to an intermediate portion of the second lever in one direction to cause the brake-shoes to be 95 released from the brake-drum, and in the opposite direction to cause the brake-shoes to be applied to the brake-drum.

5. In a friction brake, a brake-drum, two 100 brake-shoes arranged at opposite sides of the drum and adapted to frictionally engage the same, a frame beneath the brake-drum, a lever supported between its ends by the frame and supporting at one end one of the 105 brake-shoes, a second lever connected at one end to the remaining brake-shoe, means operatively connecting together the remaining ends of the levers, and means for applying force to an intermediate portion of the second lever in one direction to cause the brake-shoes to be released from the brake-drum, and in the opposite direction to cause the 110 brake-shoes to be applied to the brake-drum.

6. In a friction brake, two brake-shoes, a 115 brake-drum between them, a lever pivoted between its ends and supporting at one end one brake-shoe, an arm pivoted at one end and supporting the remaining brake-shoe at the other end, and means applied to the remaining end of the lever and to the second 120 brake-shoe for actuating both brake-shoes.

7. In a friction brake, two brake-shoes, a 125 brake-drum between them, a lever pivoted between its ends and supporting at one end one brake-shoe, an arm pivoted at one end and supporting the remaining brake-shoe at the other end, a lever connected at one end 130

to the second brake-shoe and at the other to the remaining end of the first lever, and means operating on an intermediate portion of the second lever for actuating the levers and the brake-shoes.

8. In a friction brake, two brake-shoes, a brake-drum between them, a lever pivoted between its ends and supporting at one end one brake-shoe, an arm pivoted at one end and supporting the remaining brake-shoe at the other end, a lever connected at one end to the second brake-shoe and at the other to the remaining end of the first lever, and an electromagnet having an armature operating on an intermediate portion of the second lever for actuating the levers and brake-shoes.

9. In a friction brake, two brake-shoes, a brake-drum between them, a lever pivoted between its ends and supporting at one end one brake-shoe, an arm pivoted at one end and supporting the remaining brake-shoe at the other end, a lever connected at one end to the second brake-shoe and at the other to the remaining end of the first lever, an electromagnet and an armature therefor pivoted concentrically therewith and operating on an intermediate portion of the second lever for actuating the levers and brake-shoes.

10. In a friction brake, two brake-shoes, a brake-drum between them, a lever pivoted between its ends and supporting at one end one brake-shoe, an arm pivoted at one end and supporting the remaining brake-shoe at the other end, a lever connected at one end to the second brake-shoe and at the other to the remaining end of the first lever, an electromagnet, an armature therefor pivoted concentrically therewith and with the pivot for the arm and operating on an intermediate portion of the second lever for actuating the levers and brake-shoes.

11. In a friction brake, two brake-shoes, a brake-drum between them, a frame beneath the drum, two substantially vertical pivoted

bars supporting at their upper ends the brake-shoes and supported by the frame at their intermediate and lower portions respectively, and means operating the brake-shoes and arranged wholly laterally of the brake-drum.

12. In a friction brake, two brake-shoes, a brake-drum between them, brake-shoe operating levers located on one side of a horizontal plane through the brake drum axis and the brake-shoes, means located on the said side of the plane and operatively connecting the levers, and actuating means for the brake-shoes arranged wholly laterally of the brake drum.

13. In a friction brake, a brake-drum, two brake-shoes arranged at opposite sides of the drum and adapted to frictionally engage the same, a lever pivoted between its ends and supporting at one end one of the brake-shoes, a second lever connected at one end to the remaining brake-shoe, means operatively connecting together the remaining ends of the levers, and means for applying force to an intermediate portion of the second lever in one direction to cause the brake-shoes to be released from the brake-drum, and in the opposite direction to cause the brake-shoes to be applied to the brake-drum.

14. In a friction brake, a brake drum, two brake-shoes arranged at opposite sides of the drum and adapted to frictionally engage the same, a lever supported between its ends and supporting at one end one of the brake-shoes, a second lever connected at one end to the remaining brake-shoe, means operatively connecting together the remaining ends of the levers, and means for applying force to an intermediate portion of the second lever in one direction to cause the brake-shoes to be released from the brake-drum, and in the opposite direction to cause the brake-shoes to be applied to the brake-drum.

In testimony whereof, I hereunto subscribe my name.

JAY H. HALL.
